UNITED STATES PATENT OFFICE.

JOHN WILLISON, OF CLEVELAND, OHIO, ASSIGNOR TO NATIONAL MALLEABLE AND STEEL CASTINGS COMPANY.

TRANSITION DEVICE FOR CAR COUPLERS.

Application filed July 24, 1924, Serial No. 727,852. Renewed September 14, 1926.

Fig. 1 is a plan, partly broken away, of a coupler embodying my invention with the transitional member in operating position; Fig. 2 is a side elevation, partly in section, with the parts in the same position as in Fig. 1; Fig. 3 is an elevation similar to Fig. 2 but with the transitional device in non-operating position; Fig. 4 is a plan, partly in section, with the parts as shown in Fig. 10 3; Fig. 5 is a plan of a pair of like couplers illustrating a condition which one feature of the present invention is intended to obviate; Fig. 6 is a front elevation, partly in section, with the transitional device in non-operating position; and Figs. 7, 8 and 9 are respectively plan, front and side elevations 15 of the buffer block.

My invention relates particularly to transitional coupling mechanism and is designed 20 to provide means for permitting car couplers to be coupled with couplers of other types, such as of the draw hook connection type. To this end I have provided a transitional or supplemental coupling device 25 which can be carried by the automatic coupler and may easily be swung into and out of operative position so that the coupler may be ready for coupling with an automatic coupler of the same type or with a 30 draw hook arrangement, or any other form of car coupler. My improved device is mounted in a recess in the buffering face of the automatic coupler and provides means for closing the recess when the transitional 35 device is in non-operative position. My invention also comprises the various features which I shall hereinafter describe and claim.

Referring to the drawings, A indicates a 40 coupler of the automatic type, such as is described in my Letters Patent 1,201,665, dated October 17, 1916, and B a coupler of the draw hook type. The coupler A has a longitudinally arranged recess or slot 2, the 45 axis of which is radial to the pivotal mounting (not shown) of the coupler.

The coupler A has a buffering jaw 3, a pulling jaw 4, and a buffering face 5 intermediate said jaws. The buffering face 5 is broken by 50 the lock cavity 6, in which the lock 7 reciprocates, and by the recess 2, in which the transitional device 9 and the buffering block or member 10 operate. As is shown in Fig. 6, the lock cavity 6 and the recess 2 preferably

form a continuous opening through the buffering face 5, but to the rear of such face are separated by a longitudinally extending wall 11. The recess 2 extends rearwardly to the region of the transversely arranged bolt 12, which has the function of providing a pivotal suspension for the transitional device 9 for the buffering block 10 and for the lock actuating means 13, and also acts to reinforce the coupler against lateral stresses in buffering and draft.

The bolt 12 extends transversely through the lower portion of the coupler head with its head bearing against the intermediate wall 14 and having on its opposite end a nut 15 which is set up against the exterior of the 70 opposite side wall 16 of the coupler.

The transitional device as shown comprises a shackle 17, a trunnion nut 18, the trunnions 19 of which seat in the eyes of the shackle 17, a double screw shaft 20, the ends of which are threaded through the nut 18 and a similar nut 21, respectively, with an operating handle 22 thereon intermediate the nuts 18 and 21, and a second shackle 23 pivoted upon the trunnions of the nut 21.

As the recess 2 interrupts the lower portion of the buffering face 5, the buffering member or block 10 is provided to fill the space occupied by the recess 2 and thereby form a continuation of the buffering face 5, 85 so that as the buffering jaw 3 of an opposing coupler slides along the face 5, it cannot enter or jam in the recess 2 in such a way as to prevent coupling.

The block 10 is mounted on the bolt 12 at 90 one side of the shackle 17, and has on its under side a shoulder 24 which when the block is in use has a buffering bearing against an abutment 25 on the coupler head below the bolt 12, the block itself also having a 95 buffering bearing upon the bolt 12. A forward lateral extension 26 of the block 10 is intended to bear and be supported upon a ledge 27 on the floor of the coupler, as is shown in Fig. 4. Upon the ledge 27 is a vertically disposed projection 28 which with the abutment 25 forms a substantial support for the block 10 when under buffering blows incident to coupling.

When a coupling is desired between couplers of different types, as between the coupler A and the coupler B, the transitional device (which when not in use hangs in the

position shown in Figs. 3, 4 and 6) is swung up into horizontal position and the shackle 23 is hooked over the hook coupling B. The screw handle 22 is then rotated, thus screwing up the shaft into the nuts 18 and 21, thereby shortening the effective over all length of the transition device until the slack is taken up. As the transitional device 9 is swung up into horizontal position, the 10 shackle 17 comes into contact with the buffing block 10 and swings it upwardly and rearwardly about its pivot into the interior of the coupler head as is shown in Fig. 2, where it performs no operative function. 15 When in operative position, it will be seen that the axis of the transitional member will lie directly in the line of draft.

When the transitional device is uncoupled, which is effected by turning the handle 22 in 20 the reverse direction to provide sufficient slack to permit the shackle 23 to be slipped off the hook B, it swings down into a vertically depending position beneath the coupler head and the block 10 is then free to 25 drop by gravity into operative position with its shoulder 24 engaging the abutment 25 and its extension 26 resting on the ledge 27 in front of the projection 28. Coupling may then be effected with a like coupling and as 30 the buffing jaw 3 moves along the buffing face 5, it will slide along the forward face of the block 10, which, because of its reinforcing bearings just referred to, is enabled to resist buffing shocks and guide the 35 opposing coupler into coupled position.

The block is particularly effective in like-to-like coupling with couplers of the A type, in which the coupler of a loaded car, as it 40 comes into engagement with a coupler of an unloaded car, is at a lower level than that of the unloaded car. In such an event, if no guiding member is employed in the slot 2 as is indicated in Fig. 5, the corner *a* of the buffing jaw 3 as it slides along the guiding 45 and buffing face 5, is apt to engage in the recess inside of the point *b*, and this will prevent the jaw 2 from moving far enough into the crotch 29 to permit the locks to drop into locked or coupled position, and in addition may cause damage to one or both couplers. When, however, the block 10 is 50 employed, its forward face forming as it does a continuation of the guiding and buffing face 5, prevents the corner *a* of the buffing jaw 3 from engaging the point *b*, and permits the buffing jaw 3 to slide into the crotch 55 29 and the locks will then drop into locked or coupled position.

The terms and expressions which I have 60 employed are used as terms of description and not of limitation, and I have no intention, in the use of such terms and expressions, of excluding any mechanical equivalents of the features shown and described, or portions thereof, but recognize that various

structural modifications are possible within the scope of the invention claimed.

What I claim is:

1. Transitional coupling mechanism for coupling together couplers of different types 70 one of which is an automatic coupler comprising a coupling member pivotally attached to and carried by the automatic coupler and arranged to swing freely in a vertical plane, the said coupler having a buffing 75 face and a slot extending forwardly through the buffing face from the region in which the said member is pivoted thereto, and means for closing the forward end of said slot when the transitional member is in non-operative 80 position to prevent interference in coupling with a like coupler.

2. Transitional coupling mechanism for coupling together couplers of different types comprising a coupling member pivotally attached to one of the said couplers and arranged to swing freely in a vertical plane, 85 the said coupler having a buffing face and a slot extending forwardly through the buffing face from the region in which the said member is pivoted thereto, the axis of the slot being on a radius of the pivotal mounting of the said coupler, and means for closing the forward end of said slot when the member is in non-operative position to prevent interference in coupling with a like coupler, the closing means being moved to non-operative 90 position by the transitional member when the transitional member is in operative position.

3. Transitional coupling mechanism for coupling together couplers of different types comprising a coupling member pivotally attached to one of the said couplers and arranged to swing freely in a vertical plane, 105 the said coupler having a buffing face and a slot extending forwardly through the buffing face from the region in which the said member is pivoted thereto, and means for closing the forward end of said slot when the member is in non-operative position to prevent interference in coupling with a like coupler, the said means comprising a block movable 110 by the transitional member into non-operative position when the said member is in 115 operative position.

4. Transitional coupling mechanism for coupling together couplers of different types one of which is an automatic coupler comprising a coupling member pivotally attached 120 to and carried by the automatic coupler and arranged to swing freely in a vertical plane, the said coupler having a buffing face and a slot extending forwardly through the buffing face from the region in which the said member is pivoted thereto, and a guiding device 125 having a pivotal connection with said coupler and forming a continuation of the buffing wall across said slot when the said member is in non-operative position.

5. Transitional coupling mechanism for coupling together couplers of different types one of which is an automatic coupler comprising a coupling member pivotally attached to and carried by the automatic coupler and arranged to swing freely in a vertical plane, the said coupler having a buffing face and a slot extending forwardly through the buffing face within which the member and block are pivoted to the said coupler, the coupling member being arranged to engage and rotate the block into non-operative position when the member is rotated into coupling position. 40
- 10 8. A coupler head of the vertical plane type having a buffing jaw and a pulling jaw, a lock, a transitional member, a buffing block, a buffing and guiding face intermediate said jaws apertured for the lock and the transitional member and the buffing block, lock operating means, a bolt extending transversely of the coupler head upon which the member and block and lock operating means are pivotally mounted, the lock and block comprising means for preventing a like coupler from failing to couple with the coupler head the lock, the buffing block and the lock operating mechanism being operative in coupling with a like-to-like coupler and the transitional member being operative in coupling with an unlike coupler. 50 55
- 15 20 25 30 35 9. A coupler head of the vertical plane type having a buffing jaw and a pulling jaw, a transitional member and a buffing block mounted in the coupler head operable in a vertical plane, a buffing and a guiding face intermediate said jaws having a slot therein for the transitional member and the buffing block, one of which is non-operative when the other is operative, the buffing block when 60 65 70 75 in operative position forming a continuation of the buffing face.
5. Transitional coupling mechanism for coupling together couplers of different types comprising a coupling member and a buffing block pivotally attached to one of the said couplers, the coupling member being arranged to swing freely in a vertical plane into coupling and non-coupling positions, the said coupler having a buffing face and a slot extending forwardly through the buffing face within which the coupling member and block are pivoted to the said coupler, the block having a supporting bearing on the coupler head when in operative position and being rotatable into the interior of the head into non-operative position.
6. Transitional coupling mechanism for coupling together couplers of different types comprising a coupling member and a buffing block pivotally attached to one of the said couplers, the coupling member being arranged to swing freely in a vertical plane into coupling and non-coupling positions, the said coupler having a buffing face and a
